UNITED STATES PATENT OFFICE

2,384,748

COUPLER

Edmund P. Kinne and Frank H. Kayler, Alliance, Ohio, assignors to American Steel Foundries, Chicago, Ill., a corporation of New Jersey

Application October 23, 1943, Serial No. 507,382

13 Claims. (Cl. 213—104)

Our invention relates to a well known type of tight lock industrial coupler, described in detail in United States Patent 2,271,770, issued February 3, 1942, in the name of Edmund P. Kinne and United States Patent 2,271,839, issued February 3, 1942, in the name of Frank H. Kayler, and is concerned particularly with auxiliary unlocking means for such a type of coupler.

In a coupler of this general description, the operating arm is so designed that it may be actuated by a side pull in a manner commonly convenient where such a coupler is used. Under certain conditions, however, it may be desirable to use other means for actuating the operating arm and in order to accommodate such conditions, we have arranged cam means for engagement with the operating arm, which cam means may be utilized, when desirable, in conjunction with various means for actuation thereof. The general object of our invention, therefore, is to provide auxiliary means for actuation of the operating arm of this type of coupler, said auxiliary means being arranged to accommodate various actuating means therefor suitable for use under varying operating conditions.

Our invention comprehends an arrangement for top operation of such a coupler which may be actuated by a rearward pull as well as a bottom operation which may be actuated by a side pull and a further top operation which may be actuated by a lifting movement, all in conjunction with said afore-mentioned cam.

In the drawings,

Figure 1 is a fragmentary top plan view of mated couplers of this type embodying our invention, a portion of the top walls of said couplers being cut away for purposes of illustration.

Figure 2 is a horizontal sectional view through the mated couplers illustrated in Figure 1, the top walls being entirely cut away.

Figure 3 is a vertical sectional view through the mated couplers illustrated in Figure 1, the section being taken substantially in the transverse vertical planes indicated by the line 3—3 of Figure 1.

Figure 4 is a further sectional view comparable to that of Figure 3 but taken in the vertical transverse plane approximately indicated by the line 4—4 of Figure 2.

Figure 5 is a sectional view comparable to Figure 2 with the top walls of the mating couplers cut away to illustrate a modified form of cam arrangement.

Figure 6 is a fragmentary sectional view through the top wall of one of the couplers illus-

trated in Figure 5, the section being taken in the vertical diagonal plane adjacent and approximately parallel to the cam actuating lever.

Describing our novel structure in detail, and referring first to the modifications illustrated in Figures 1 to 4, it may be observed that mating couplers 2 and 4 are in locked engagement with each other with the locking faces of the respective locks abutting each other as at 6. The positions of the various locking parts of each coupler are well shown in the sectional view of Figure 3 wherein it may be noted that each lock 8 has an associated operating arm 10 pivotally connected thereto as at 12, said operating arm having a spring seat 14 against which may abut as at 16 the associated compression spring 18, said compression spring surrounding the operating arm and having its opposite end seated as at 20 against the side wall 22 of the nose portion of the associated coupler, said nose portion being received within the head 24 of the mating coupler. With the parts in the locked position as illustrated in Figure 3, each operating arm 10 is afforded an anticreep as at 26 by engagement of a shoulder on the operating arm with an abutment on the side wall of the mating coupler head. It will be understood that under ordinary conditions, unlocking will be effected by lifting the end of the operating arm 10 in order to clear the shoulder engagement at 26 and withdrawing it sufficiently to engage the lockset (Figure 4), thus rotating one lock to its lockset position.

As well shown in Figures 1 and 2, each of the mating couplers is afforded a cam member 28 pivotally mounted as at 30 in the associated coupler head, each cam 28 comprising an operating arm 31 (Figure 2) terminating in a finger 32 (Figures 3 and 4) which may engage as at 34 the lower edge of the spring seat portion 14 of the associated operating arm. As illustrated in coupler 2 of Figure 1, the cam 28 may have associated therewith an L-shaped operating lever 36 keyed to said cam as at 38, and actuation of said cam by the lever 36 in the direction of the curved arrow 40 is effective to move the associated operating arm 10 to the lockset position illustrated in Figure 4. It will be understood that the bearing of the cam finger 32 as at 34 against the operating arm 10 will pivot said arm about the lock connection 12, thus lifting the outer end of the operating arm 10 out of engagement with the anti-creep shoulder at 26 and causing it to engage the lockset shoulder at 42 (Figure 4) where it will be held in position by the compression spring 18.

As illustrated in the coupler 4 of Figures 1 and

55

2, it may be noted that the cam 28 is afforded keyed engagement as at 44 with the L-shaped lever 46, which projects above the top wall of the coupler 4 and laterally thereof, so that said lever 46 when pulled in the direction of the arrow 48 will be effective to actuate the cam 28 and position the associated lock in the lockset position of Figure 4 in manner similar to that just described for the mating coupler. It will be understood, of course, that either the lever 36 or the lever 46 may be used with the cam 28, depending upon whether a bottom operating coupler or a top operating coupler better meets the required conditions.

A further modification for actuation of such a cam as that described is illustrated in Figures 5 and 6. Figure 5 shows the mated couplers 102 and 104 in engagement with each other with the lock 106 of the coupler 102 in lockset position, the parts thereof corresponding to the positions illustrated in Figure 4 with the operating arm 108 of the coupler 102 lockset against the shoulder on the side wall of the mating coupler 104. With the parts in this position, parting of the two couplers will cause release of the arm 10 from its lockset position in notch 42 of mating coupler due to the notch portion 42 being withdrawn from engagement with arm 10 as couplers part.

As illustrated in Figure 5, the cam 112 differs from the cam of the previous modifications in that it is afforded an auxiliary arm 114 projecting from the cammed trunnion portion 116 in a direction opposite the arm 112, said arm 114 affording suitable means of engagement as at 118 (Figure 6) with the depending leg 120 of the lift lever 122 which may be pivotally supported as at 124 in the top wall 126 of the coupler 102, a portion of said top wall being offset, as well illustrated in Figure 6, to form a housing for the pivoted end of said lever 122. The normal position of the lever 122 when at rest is shown in phantom lines 128, and the position of said lever when elevated to afford the before-mentioned lockset is shown in Figure 6.

It will thus be seen that by mounting the cam in the coupler head as auxiliary means for actuating the operating arm, we are able to afford a variety of ways for locksetting or unlocking the locking mechanism of this type of coupler. The several means for actuating such a cam, as illustrated, provide for top operation by direct upward pull or a rearward pull on the cam actuating lever, or may provide bottom operation by a side pull on the cam operating lever. It will be understood that under certain clearance conditions, each of these respective means of operation may become necessary or desirable.

It is to be understood that we do not wish to be limited by the exact embodiments of the device shown which are merely by way of illustration and not limitation as various and other forms of the device will, of course, be apparent to those skilled in the art without departing from the spirit of the invention or the scope of the claims.

We claim:

1. In an automatic coupler, a head, a lock mounted for rotation therein, and lock operating means comprising an operating arm pivotally connected to said lock and projecting outwardly of said head for actuation thereof, auxiliary means for actuating said arm comprising a cam mounted to rotate in said head and abut said arm beneath said pivotal connection, said cam being operable to rotate said arm about said pivotal connection for disengagement of an anticreep on

said arm and cause linear movement of said arm for engagement of a lockset shoulder thereon with means on an associated coupler head, and lever means keyed to said cam and projecting outwardly of said head for operation thereof.

2. In an automatic coupler, a head, a lock mounted for rotation therein, and lock operating means comprising an operating arm pivotally connected to said lock and projecting outwardly of said head for actuation thereof, and auxiliary means for actuating said arm comprising a cam mounted to rotate in said head and abut said arm beneath said pivotal connection, said cam being operable to rotate said arm about said pivotal connection for disengagement of an anticreep on said arm and further operable to cause linear movement of said arm for engagement of a lockset shoulder thereon with means on an associated coupler head.

3. In an automatic coupler, a head having a pivoted lock and lock operating means comprising an operating arm pivotally connected thereto and projecting outwardly of said head for actuation thereof, and alternative actuating means for said arm comprising a cam mounted for rotation in said head and having a leg engaging said arm and another leg angularly related to said first-mentioned leg, and a crank lever mounted on the top of said head and having a leg projecting thereto for engagement with one of said cam legs for actuation thereof, said alternative actuating means being operable to rotate said operating arm about its pivotal connection with said lock and to apply linear movement thereto for engagement of lockset means.

4. In an automatic tight lock coupling, mating coupler heads having pivoted locks with locking faces for abutment with each other and unlocking means for each coupler comprising an operating arm pivotally connected to the associated lock and having a lockset shoulder for engagement with the mating coupler, and actuating means for said arm comprising a cam pivoted in the associated head and engaging said arm adjacent said lock connection, and a lever keyed to said cam and projecting outwardly of the associated head for rotation thereof.

5. In an automatic tight lock coupling, mating coupler heads having pivoted locks with locking faces for abutment with each other and unlocking means for each coupler comprising an operating arm pivotally connected to the associated lock and having a lockset shoulder for engagement with the mating coupler, and actuating means for said arm comprising a cam pivoted in the associated head and engaging said arm adjacent said lock connection, and a lever keyed to said cam and projecting beneath the associated head for rotation thereof.

6. In an automatic tight lock coupling, mating coupler heads having pivoted locks with locking faces for abutment with each other and unlocking means for each coupler comprising an operating arm pivotally connected to the associated

lock and having a lockset shoulder for engagement with the mating coupler, and actuating means for said arm comprising a cam pivoted in the associated head and engaging said arm adjacent said lock connection, and a lever keyed to said cam and projecting above the associated head for rotation thereof.

7. In an automatic coupler, a head having a pivoted lock and lock operating means comprising an operating arm pivotally connected thereto and projecting outwardly of said head for actuation

thereof, and alternative actuating means for said arm comprising a cam mounted for rotation in said head and having a leg engaging said arm and another leg angularly related to said first-mentioned leg, and means mounted on said head for engagement with said angular leg for rotation of said cam and movement of said arm, said alternative actuating means being operable to rotate said arm about its pivotal connection with said lock to disengage an anticreep therefrom, and further operable to apply linear movement to said arm for engagement of lockset means.

8. In an automatic coupler, a coupler head, a rotatable lock mounted therein, an operating arm pivoted to said lock and projecting outwardly of said head for actuation thereof, and alternative actuating means for said arm comprising a cam pivoted in said head and engaging said arm adjacent its connection with said lock, engagement of said cam with said arm being operative to rotate said arm about its connection with said lock for elevation of the projecting end thereof, and further operative to cause linear movement of said arm for engagement of lockset means on an associated coupler head.

9. In an automatic tight lock coupling, mating coupler heads having pivoted locks with locking faces for abutment with each other and unlocking means for each coupler comprising an operating arm pivotally connected to the associated lock and having a lockset shoulder for engagement with the mating coupler, and actuating means for said arm comprising a cam pivoted in the associated head and engageable with said arm adjacent said lock connection, for rotation thereof about its pivotal connection with the associated lock to disengage said arm from an anticreep on the associated coupler, said cam being further operable to move said arm linearly and cause its engagement with lockset means on the mating coupler head.

10. In an automatic coupler, a head, a lock mounted for rotation therein, and lock operating means comprising an operating arm pivotally connected to said lock and projecting outwardly of said head for actuation thereof, and auxiliary means for actuating said arm comprising a cam mounted to rotate in said head and abut said arm beneath said pivotal connection to cause rotation

5 of said arm about said pivotal connection and to further cause linear movement of said arm for engagement of lockset means on an associated coupler head, and lever means keyed to said cam and projecting outwardly of said head for operation thereof.

11. In an automatic coupler, a coupler head, a lock pivoted therein, lock actuating means comprising an operating arm pivotally connected to said lock and projecting outwardly of said head for actuation thereof, and auxiliary actuating means for said arm comprising a cam mounted in said head and engageable with said arm beneath said pivotal connection to said lock to cause elevation of said outwardly projecting portion of said arm for disengagement of anticreep means, said cam being further operable to apply linear movement to said operating arm and cause engagement of lockset means on an associated coupler head.

12. In an automatic coupler, a head, a lock mounted for rotation therein, and lock operating means comprising an operating arm pivotally connected to said lock and projecting outwardly of said head for actuation thereof, and auxiliary means for actuating said arm comprising a cam mounted to rotate in said head and actuate said arm by engagement therewith beneath said pivotal connection, said actuation disengaging said arm from anticreep means on said head, and said auxiliary means being further operable to cause linear movement of said arm for engagement with lockset means on an associated coupler head.

13. In an automatic coupler, a coupler head, a rotatable lock mounted therein, an operating arm pivoted to said lock and projecting outwardly of said head for actuation thereof, and alternative actuating means for said arm comprising a cam pivoted in said head and engaging said arm adjacent its connection with said lock, said cam being operable to rotate said arm about its pivotal connection with said lock to elevate the remote end thereof for disengagement of anticreep means on said head, and further operable to move said arm for engagement of lockset means on an associated head.

EDMUND P. KINNE.
FRANK H. KAYLER.
